NEUROSURGICAL SUCTION DEVICE

Bertil Sven Vällfors, Goteborg, Sweden, assignor to
Medena AB, Kungsbacka, Sweden

Filed Dec. 15, 1971, Ser. No. 208,515

Term of patent 14 years

Int. Cl. D24—04
U.S. Cl. D83—12

FIG. 1

FIG. 2

FIG. 3

FIG. 1 is a perspective view of a first embodiment of a neurosurgical suction device;

FIG. 2 is a perspective view of a second embodiment of the neurosurgical suction device illustrated in FIG. 1;

FIG. 3 is a perspective view of a third embodiment of the device.

I claim:

The ornamental design for a neurosurgical suction device, as shown and described.
